CLAIM

The ornamental design for a device for golf clubs, as shown and described.

DESCRIPTION

FIG. 1 is a top, front, and right side perspective view of a device for locking golf clubs showing my new design, the broken-line disclosure of a portion of a golf bag and clubs being for illustrative purposes only and forming no part of the claimed design;

FIG. 2 is a front elevational view thereof, the rear being a mirror image of that shown;

FIG. 3 is a right side elevational view thereof;

FIG. 4 is a left side elevational view thereof;

FIG. 5 is a top plan view thereof; and,

FIG. 6 is a bottom plan view thereof.
